The open metal framework includes upright components, such as columns, pillars and posts having substantially flat side surfaces, and includes modular length transverse components, such as relatively heavy main beams and relatively lighter connecting beams having flat side and end surfaces. Connecting means, such as bolts and the like secure the flat end surfaces of the transverse components to the flat side surfaces of the upright components and to flat side surfaces of other transverse components to form skeleton wall and floor sections having openings defined by substantially flat surfaces of the components. At least two sets of prefabricated molded modular length panels, of cementitious material, are mounted on the sections and close at least some of the openings therein. At least the transverse components have longitudinal lips, and mechanical means are engaged with these lips and secure the panels to at least the transverse components. The panels have a composition similar to conventional masonry and exterior panels may be formed in the same manner as ceramic tiles. The lower edges of the panels rest on projecting plates on lower transverse components of the framework.

PREFABRICATED BUILDING STRUCTURE
INCLUDING METAL FRAMEWORK AND
PREFABRICATED MOLDED PANELS OF
CEMENTITIOUS MATERIAL

FIELD OF THE INVENTION

This invention relates to prefabricated building structures and, more particularly, to a simpler, less expensive, and more desirable prefabricated building structure involving an open metal framework having at least some openings closed by molded modular length panels of cementitious material.

BACKGROUND OF THE INVENTION

Modern construction techniques are usually directed to two types of prefabrication, namely a heavy type which is not widely used and a light type, which is widely used. Both types of prefabrication include the setting up of panels of large dimensions which are prefabricated in a yard.

Heavy prefabrication is not used widely because it has no "flexibility." In fact, and owing to its nature, it requires setting up of constructions which are all similar and uniform. Light prefabrication, on the other hand, is more flexible and has found a wide field of use.

The main defects of light prefabrication involve, in addition to the high cost, the quality of the materials used in such a system. In a construction using light prefabrication materials, the human body is not comfortable, as the materials are not suited to favor thermic exchange between the human body and the ambient atmosphere. Furthermore, the light types of construction are effected very sharply by exterior climatic variations, do not have any capacity for a thermic balance, and do not modulate the moisture content of the ambient atmosphere. Instead, they tend to emphasize this moisture content.

The conventional system provides for constructions made with load bearing structures of concrete or of steel sections, and the walls are constituted by tiles with a large amount of binder, such as cement mortar. All these materials have qualities which are unsuited to the comfort of the human body.

SUMMARY OF THE INVENTION

In accordance with the present invention there is provided, in addition to the steel carrying structures already known and used, a steel skeleton for all the walls of a prefabricated building. The invention includes a lining of the entire framework with relatively small panels made of sand-cement or similar cementitious material, these panels being more or less finished. The materials selected for the panels combines the advantages of a reduced cost and a better adaptation to ambient comfort conditions. In fact, the material of the panels performs, in proportion to its weight, the function of a thermic and hygroscopic flywheel. The assembly is similar to that of a mechanical system, in order to obtain quickness and accuracy of the assembling or erecting operations.

To this end, the invention is directed to a prefabricated structure for buildings and, in particular, to walls including a skeleton of metal elements connected with one another by threaded means to form flat limiting surfaces capable of being lined by panels of cementitious material, such as sand-cement or the like, secured

to the metal elements of the skeleton by mechanical means.

In practice, the skeleton may be formed by flat drilled posts and by horizontal transverse components having modular lengths, the horizontal and upright components being connected to each other by pairs of threaded members, such as bolts or screws, to assure the planarity of the skeleton. The transverse components are formed with longitudinal lips or flanges for anchoring of the panels. The posts and the transverse components are suited further to define limiting surfaces of recesses for doors and windows. In particular, lower transverse components are provided with projecting plates for the support or laying of the panels.

15 In accordance with the invention, pairs of spacers are advantageously provided, and are designed to interconnect posts arranged at an adjustable distance from each other, to modify the size of the skeleton with respect to the modular sizes or dimensions.

20 In practice, a wall skeleton may be used for padding walls of nets formed by a carrying frame. Such a skeleton is connected to the carrying frame by pins which allow relative motion, and thus without any rigid interconnections. The pins may be integral with the frame and accommodated in apertures of the posts or strut of the wall section.

25 The panels are formed in pressing molds in order to obtain accuracy of shape and dimensions and an accurate positioning of the contours or shapes, seats, holes, or eyelets arranged for securing the panels to the skeleton with a mechanical type accuracy.

30 The panels may be formed, along their edges, with either holes, slots, or depressions, arranged to facilitate connection of the panels to the transverse components by means of clips, stirrups, screws, bolts, or similar mechanical means, which are hooked to the edges of the transverse components. The securing means are positioned in depressions of the panels, which depressions may be covered with stucco or plaster.

35 In accordance with an embodiment suitable for the use of finished panels on the exposed surface, the panels have combined therewith hook type pins projecting from rear depressions. These pins are designed for anchoring or fixing of metal wires for the mutual interconnection of adjacent panels or for the connection of a panel to the metal skeleton. For connection of the panels to the edges of the transverse components, the latter may be formed with an inwardly bent lip or flap with which elements, formed with two oppositely directed slots, may be engaged, with one slot serving for engagement with the flap of the transverse component and the other slot serving for engagement with a metal wire or tie. In this case, assembly may be effected on the rear of the finished surface.

40 45 50 55 60 65 The finished panels may be produced by the technique used in forming ceramic tiles or the like.

Covering panels also may be used, these panels being engageable to the walls panels to form a waterproof lining or covering. The covering panels may be fixed into engaging means secured in holes in the wall panels.

The prefabricated building structure may include horizontal paneling forming floors and ceilings, utilizing panels similar to the wall panels, anchored by clips, stirrups, threaded connections, or the like to a supporting floor and ceiling carrying framework.

In order to improve the sound-proofing effect, suitable deadening material may be interposed between

two series of panels assembled against opposite surfaces of the metal skeleton.

An object of the invention is to provide an improved prefabricated building structure.

Another object of the invention is to provide such a structure including a wall and floor-carrying open metal framework having upright components with substantially flat side surfaces and modular length transverse components having substantially flat side and end surfaces. A further object of the invention is to provide such a structure including connecting means securing the flat end surfaces of the transverse components to the flat side surfaces of upright components or of other transverse components to form skeleton wall and floor sections having openings defined by substantially flat surfaces.

Another object of the invention is to provide such a structure including at least two sets of prefabricated molded modular length panels of cementitious material mounted on the sections enclosing at least some of the openings therein.

A further object of the invention is to provide such a structure in which the transverse components have longitudinal lips, and mechanical means are engaged with the lips and secure the panels to at least the transverse components.

For an understanding of the principles of the invention, reference is made to the following description of typical embodiments thereof as illustrated in the accompanying drawing.

BRIEF DESCRIPTION OF THE DRAWING

In the drawing:

FIG. 1 is a partial plan view, partially in horizontal section, of a structure of prefabricated elements embodying the invention;

FIG. 2 is a vertical sectional view taken on the line II—II of FIG. 1;

FIG. 3 is a perspective view of a wall, formed in accordance with the invention, and only partly lined with panels;

FIG. 4 is a partial perspective view illustrating the completely lined wall;

FIG. 5 is a partial front elevation view illustrating only the framework;

FIG. 6 is a vertical section of a portion of a covering structure and an underlying ceiling, embodying the invention;

FIG. 7 is a horizontal sectional view of a floor structure embodying the invention;

FIGS. 8 and 9 are enlarged detailed sectional views corresponding to the arrows VIII and IX of FIG. 6;

FIG. 10 is a sectional view illustrating the interconnection between two adjacent panels;

FIG. 11 is a front elevation view illustrating the paneling;

FIG. 12 is an enlarged detailed sectional view taken on the line XII—XII of FIG. 3;

FIG. 13 is an enlarged detailed sectional view illustrating a detail of an angular connection between mutually perpendicular walls;

FIGS. 14, 15 and 16 are sectional views illustrating three different details of linings;

FIG. 17 is a sectional view taken along the line XVII—XVII of FIG. 16;

FIG. 18 is an enlarged detail corresponding to the arrow XVIII of FIG. 15;

FIG. 19 is a perspective detail of an outer lining embodying the invention;

FIG. 20 is a sectional view taken along the line XX—XX of FIG. 19;

FIGS. 21 and 22 are sectional views illustrating two different outer covering plates;

FIG. 23 is a perspective view illustrating the rear of a plate such as shown in FIGS. 21 and 22;

FIG. 24 is a perspective view of a panel embodying the invention;

FIG. 25 is an enlarged perspective view illustrating a detail of the panel;

FIGS. 26 and 27 are sectional views taken along the lines XXVI—XXVI and XXVII—XXVII, respectively, of FIG. 24;

FIG. 28 is a sectional view illustrating a wall assembled with two different forms of anchoring means;

FIG. 29 is a partial perspective view of a surface finished panel used in the wall shown in FIG. 28;

FIG. 30 is an overall perspective view, partly in section, of a construction embodying the invention;

FIGS. 30A and 30B are enlarged partial perspective views, partially in section, illustrating a floor, illustrated at A in FIG. 30, and a wall, illustrated at B, in FIG. 30, respectively;

FIG. 31 is a perspective view, partly in section, illustrating an outer wall and a covering therefor;

FIG. 32 is an enlarged vertical sectional view illustrating a detail of the connection between main beams and cross beams of a floor;

FIG. 33 is a cross sectional view of a lattice-work element illustrating two different panel securing means;

FIG. 34 is a vertical sectional view of upper and lower wall guides corresponding to a post of a wall section;

FIG. 35 is a partial longitudinal sectional view taken along the line XXXV—XXXV of FIG. 34;

FIGS. 36 and 37 are illustrations of two different embodiments of T-shape connections between wall guides;

FIG. 38 is a partial plan view illustrating aligned wall guides interconnected by a slotted sleeve;

FIG. 39 is a cross sectional view taken along the line XXXIX—XXXIX of FIG. 38;

FIG. 40 is a sectional view illustrating the interconnection of a wall skeleton post with the skeleton of another wall ascending at right angles to the first wall;

FIGS. 41 and 42 are horizontal sectional views illustrating details of outer walls combined with the main framing of the building structure;

FIG. 43 is a view taken along the line XLIII—XLIII of FIG. 41;

FIG. 44 is a vertical sectional view illustrating details of the connection of secondary beams to a main floor beam;

FIG. 45 is an elevation view, partly in section, illustrating a bracing of a vertical wall; and

FIG. 46 is a sectional view illustrating a detail of the connection of the bracing.

DESCRIPTION OF THE PREFERRED EMBODIMENTS

Referring particularly to FIGS. 1 through 29 of the drawing, to construct the prefabricated building structure there is provided a carrying frame, preferably of iron or steel treated with an anti-oxidizing process, in which the support structure comprises posts and main

horizontal beams, respectively indicated at 1 and 3 in the drawing. The elements constituting the frame are preferably interconnected by bolting rather than by welding, in order to avoid any deformations or strains and to assure accurate assembly.

The floor of the framework comprises beams 3, shown more particularly in FIG. 7, interconnected by cross girders or transverse components 3A. The floor itself comprises relatively thick, appropriately reinforced concrete panels 5, and these panels are anchored to the upper flanges of beams 3, 3A, or both in a manner described hereinafter and which is substantially equivalent to the manner used for connecting the wall panels to the supporting framework.

The panels 5 are similar to the wall panels shown, more particularly, in FIGS. 24 through 27, and which are formed around their peripheries with recesses or depressions 7 having inner enlarged ends, which are preferably circular, indicated at 7A. These recesses 7 are aligned on opposite surfaces of each panel, and are interconnected by through holes 9 at the centers of the circular enlargements 7A. The two recesses of each pair, aligned on opposite surfaces of a panel, are separated by webs 7B.

Floor panels 5 are laid on the upper flanges of the beams 3 and 3A, and are butted against each other in a manner such that connection stirrups 11, or other suitable connection means, may be inserted through holes 9 to be engaged with the flanges of the beams or with the webs 7B. The stirrups 11, as well as any other equivalent connection elements, are entirely accommodated in the recesses or depressions 7, 7A, and are then appropriately covered with stucco or the like without any projections showing. FIG. 7 also illustrates a variation of the connection stirrups 11, which have a substantial U-shape, this variation comprising threaded hooks 13 serving the same purpose and receiving nuts accommodated in the recesses 7A, the connections again being covered with stucco.

The ceiling is formed from panels 15, which may be concrete or reinforced cement, but which are thinner than the floor panels 5. Panels 15 are connected to the flanges of beams 3 and 3A by connection means 17 and 19 similar to the respective connection means 11 and 13.

The main open metal framework supports the exterior walls of the structure, and these exterior walls are formed with window and door openings. The exterior walls, as well as the interior partition walls, comprise a composite metal skeleton and closing panels of concrete or cement, and which are relatively light panels. The metal skeletons are formed independently of the supporting framework and mounted thereon so as to permit relative movement, thus avoiding the known disadvantages of conventional structures. As best seen, for example, in FIGS. 3, 4 and 5, a metal wall skeleton comprises relatively elongated substantially rectangular plates forming posts 21, and these posts are interconnected by transverse components of three types, including intermediate components 23, lower components 25 and upper components 27. FIGS. 3, 4, 5 and 12 illustrate, in particular, an inner wall, or at least a wall of limited thickness. For this purpose, the skeleton is formed by the posts 21 which define the thickness of the wall, less the two thicknesses of the paneling enclosing the metal skeleton of the wall. Posts 21 are interconnected by double intermediate transverse com-

ponents 23 of pressed sheet metal, having rectangular end lips or flanges 23A for connection to posts 21 when holes in the flaps 23A are aligned with corresponding holes in the posts 21. Transverse components 23 furthermore have flanges 23B for connection of the panels thereto in a manner described hereinafter.

At their lower ends, posts 21 are connected with the transverse components 25 which also have end lips or flanges 25A and have flanges 25B extending along the 10 opposite edges. The lower transverse components 25 are further provided with underlying plates 25C designed to support the panels which project laterally beyond the flanges 25B. At their upper ends, posts 21 are interconnected by the upper transverse components 27 which are similar to the lower transverse components 25 but do not have associated therewith plates corresponding to the plates 25C. In effect, the transverse components 25 and 27 are similar to the intermediate transverse components 23, but are not arranged in superposed pairs as are the components 23.

The metal framework of a relatively thin wall is enclosed, on its opposite surfaces, with panels 25 of a type completely similar, except for thickness and the eventual amount of internal reinforcement, to the panels 5 described and illustrated with respect to FIGS. 24 through 27 and used as floor panels. The wall panels 29, as best seen in FIG. 12, are connected by stirrups 31, screw hooks 33, or other equivalent means to the flanges 23B, 25B and 27B of the respective transverse components 23, 25 and 27 which are spaced apart in a modular manner or a pitch corresponding to one of the two dimensions of the panels 25. The wall thickness in this case is, as mentioned above, equal to the width of post 21 plus twice the thickness of panels 29.

Panels 29 may be assembled with their longer sides vertical, as shown in FIG. 3, or with their longer sides horizontal, as shown in FIG. 4, in accordance with the particular requirements, and the panels are dimensioned advantageously so that the longer side has a length twice the shorter side. The transverse components of the framework are arranged with a spacing therebetween corresponding to the dimensions of the panels to be applied thereto in a preselected orientation. While those panels having their edges extending along and corresponding to the transverse components 23, 25 and 27 are connected with these components with means, such as indicated at 31 and 33, and where the panels abut each other at their side edges, where the panels abut at locations where there are no transverse components they may be interconnected with each other by links 35, as shown in FIG. 10, or by other suitable connecting means. In any case, the panels may also be adhered to each other along their abutting edges, and their recesses 7, 7A are appropriately filled with stucco to cover the connecting means. The panels of the lower row have their lower edges supported on plates 25C underlying the lower transverse components 25. However, and in the absence of the underlying plates 25C, the lower edges of the lower row of panels may be supported directly on floor panels 5.

Even if the lengths of the transverse components are appropriately selected, in a modular manner, there is a possibility of gaps remaining between skeletons comprising posts 21 and transverse components 23, 25 and 27 and the space to be filled by the wall including such a skeleton. Referring to FIGS. 3 and 5, there are provided, in such a case, two posts 21X which are inter-

connected to each other, in spaced relation, with the interposition of suitable spacers 37. There is thereby attained the desired horizontal dimension for filling the space between upright components of the main supporting open metal framework.

The connection between a post or column of the open metal framework carrying structure and an adjacent end post 21 of a wall skeleton is not particularly stabilized in a rigid manner, but is effected by means of pins 41, such as shown in FIG. 5, and which are secured like studs on the post or column 1 and accommodated in corresponding openings provided for this purpose in the post 21 of the wall skeleton. Thus, each wall skeleton has limited freedom of movement relatively to the main supporting framework. Posts 21 are formed with openings for the means securing the transverse components thereto, for the spacers 31, and for service connections of the completed structure.

A wall such as described and shown in particular in FIG. 12 may form, for example, a partition wall, as indicated at 51 in FIGS. 1 and 2, with a post 21 being interposed between the two panelings 51A which are continuous and cover substantially all the wall surface. Partial panels, cut from the panels 29 having standard modular dimensions, can be used to complete the wall lining at the gaps resulting from the modular construction not being equal to the entire space to be filled.

To form walls having a greater thickness, such as the outside walls 53 shown in FIGS. 1 and 2, metal skeletons, comprising posts 21 and transverse components 23, 25 and 27, are provided in duplicate, and the two skeletons are interconnected by spacers or stiffening brackets 55. In such case, there is provided a single inner paneling 53A on the inner metal skeleton, and a single outer paneling 53B on the outer skeleton of the wall unit 53. The panelings 53A and 53B may comprise panels of the type of the panels 5, or may comprise thinner panels such as the panels 29, or any other suitable thickness panels.

The spacing between the posts 21 of each wall skeleton, and thus the length of the transverse components 23, 25 and 27, is designed in a manner so as to allow the forming of openings for doors and windows by utilizing additional transverse components of suitable length. The door and window openings are well defined by the posts 21, on their side edges, and by the transverse components which define the upper and lower edges in the manner of a threshold. The window or door frames can be easily secured to the posts 21. In the case of structures such as an outer wall 55, it is possible to arrange suitable frames therein, having the thickness of the wall, and suitably securable to posts 21 of the duplicate or dual skeletons which correspondingly define the openings receiving the frames.

In the interior of the wall 51 or 53, it is possible to accommodate lagging and sound-proofing insulating material, or both, in such a manner as to provide appropriate insulation.

FIG. 13 illustrates the connection between mutually perpendicular walls. One wall, in the plane of the drawing, includes an end post 21Y to which are connected transverse components such as, for example, those illustrated at 23Y. A block 57 is secured against post 21Y in correspondence with the end flaps or flanges 23A of transverse components 23Y and, by means of stirrups 59 secured in place by bolts 61, the longitudinal flanges 23B of transverse components such as 23Z

of a wall perpendicular to the first wall are secured to the framework of the first wall. The paneling covering the wall having the transverse components 23Z is illustrated at 51C, and the panels of paneling 51C are secured, with the means already described, to the longitudinal flanges 23B of the transverse components 23Z. Blocks or spacers, such as the block 57, are used when it is necessary to compensate for the thickness of the panels or for other differences without using the more expensive type of joint formed by two posts interconnected with the interposition of spacers.

An outer peripheral wall, such as the wall 53 shown in FIG. 2, advantageously may be lined or coated with a waterproof material or may be formed to support outer covering means which may be applied to the paneling 53B. FIGS. 19 through 23 illustrate how such an outer lining, using metal plates, for example, may be applied. The plates could be any other material, such as a synthetic resin material, having suitable dimensions to correspond, for example, to four panels 29. Lining plates of this type are indicated at 63 as having, on one edge, a flange 63A and, on the other edge, an outwardly opening channel 63B. Each plate 63 may have an outer contour formed with suitable cambers or ribs, such as shown in FIGS. 21 or 22, for esthetic and stiffening purposes. In each case, however, the inner surfaces of the plates 63 have laminar projecting elements 65 formed with notches 65A and by means of which the plates 63 may be mounted by slipping elements 65 over the stem portions of bolts 67A included between two heads 67. The bolts 67A may be secured, for example, in central openings of each of four adjacent panels. Plates 63 have dimensions such that the lower edges of the plates of one row overlap the upper edges of the plates of the next lower row, and the flanges 63A of the plates are engaged in the channels 63B of laterally adjacent plates. The panels 29 designed to be covered by the plates 63 may be preformed with apertures to accommodate the bolts 67A.

In the mounting system, a gap is provided between the sand-cement panels and the impermeable or esthetic plates, for example porcelain lamina, to obtain a true thermic insulating effect which either favors or prohibits a suitable air circulation.

For the upper covering or roof of the prefabricated building structure, there may be provided, as best seen in FIGS. 6 and 8, beams 69 in association with lighter horizontal girders 71 which receive panels 73 similar to the panels 5 or 29 lying on the components 69 and 71 and connected thereto by small links or loops 75, similar to the loops 35, and which engage the lighter horizontal girder 71. Above the shell formed by panels 73, there may be arranged a waterproof covering formed, for example, by plates or shingles 77, which may be similar to the plates 63, and which are appropriately overlapped to avoid any moisture entering the structure.

FIG. 6, in combination with FIG. 9, also shows the formation of a ceiling under the roof covering, in which includes panels 15, formed in the same manner as described, and connected by small stirrups 79 to transverse components 81 supported by a frame 83.

A prefabricated structure, after completion of the assembly, may be suitably finished, both with respect to the already described structures and with relation to the required conduits for services of different kinds, such as hydraulic, electric, etc., whose setup may be at

least partially effected by the thickness of the wall frames, the posts of the wall frameworks being suitably perforated for such purposes. On the other hand, some conduits necessarily may have to be arranged externally or only partially accommodated in the thickness provided by the vacant zones between the panels. Suitable covering means therefore are provided for the inner finishing of the rooms or premises, and examples thereof are illustrated in FIGS. 14 through 18.

In FIG. 14, for example, a corner between two walls S1 is covered and masked by a strap or gusset 85 suitably retained in position by tie rods 87 suitably anchored to the internal metal framework of the wall.

In FIG. 15, a column 1 of the main supporting framework is illustrated as completely or partially lined or covered with respect to the walls extending therefrom. In either case, bevel corner elements 82 and small panels 89 may be used, and these may be appropriately interconnected, for example as shown in FIG. 18, with the same means used for forming connections between adjacent panels of a wall. That is, the interconnection can be effected by links or loops 91 extending through holes corresponding to the recesses provided in the opposite surfaces and which recesses are later filled with stucco.

As shown in FIG. 16, the bevel corner members 85, in connection with panels 89A, may be used to form a box for accommodating pipes 93 or other conduits which are partially set in the thickness of the panels 29, which have a suitable gap therebetween. The covering 85, 89A may be suitably anchored by tie rods 95. These connections are further illustrated in FIG. 17.

The supporting structures and the wall skeletons comprising the metal elements are assembled by means of bolts, rather than by welding which could result in strains or deformations.

The panels are formed by wet pressing, in general with 10 percent moisture present in the cement pressing system. This improves the function of hygroscopic equalizers required in the panels, which latter are porous.

The dimension of panels formed as described, in sand-cement or the like, is important and must comply with several conditions. Thus, the dimensions must be modular and preferably the panels are rectangular with the longer side having a length twice that of the shorter side, to permit a mixed assembly with a longer side either vertical or horizontal. The weight, that is the mass, of each panel must be sufficiently high to meet the conditions required for maintaining comfortable ambient conditions but, on the other hand, the panels must be sufficiently light with respect to the cost of transport and further to facilitate handling during the assembly. Furthermore, the panels must be susceptible of being pressed in mass production without any rejections, using an automatic plant, and providing panels having suitable sizes and at a low cost. For instance, the panels may have lateral dimensions of 30 x 60 cm.

In constructing a prefabricated building structure embodying the invention, the foundation and underground structures are provided by conventional methods. Subsequently, the main supporting framework, including the floor beams and the roof beams, having modular sizes, is erected using bolts. The wall skeletons, including the components 21, 23, 25 and 27 are preassembled, and then mounted on the main supporting framework. Following this, the heating, sanitary,

electric, and like systems are provided, after which there is a general inspection. Finally, the wall frameworks are lined using the panels, followed by assembly of the floors, painting, and like procedures.

5 It should be noted that a wall skeleton comprising the posts and the transverse components, for filling the openings of the main supporting framework, provides a flat surface in which the screws or bolts are effective in the direction of the post width and in such a manner 10 as to assure planarity of the skeleton. The posts have the function of being connected to the transverse components, of limiting the lengths, and of providing flat limiting surfaces for door and window openings.

In paneling a room, while recourse may be had to the 15 straps or gussets such as shown in FIG. 14, there also may be utilized a panel arrangement in which a panel of one wall overlaps and lies against the end edge of a panel of a wall perpendicular to the one wall.

FIGS. 28 and 29 illustrate an embodiment which is 20 modified, with respect to some details, with respect to the embodiments already described. In these figures, the posts of the metal skeleton of a wall are indicated at 101, and the transverse components are indicated at 103, the components 103 comprising two symmetrical 25 sections secured in back-to-back relation by spot-welding or in any other suitable manner. Each transverse component has right angle end flaps or flanges 103A for securement to a post utilizing pairs of screws or bolts. Furthermore, each transverse component also 30 has flanges 103B extending along each inner edge and having inturned lips 103C extending along their free edges, for the purpose of stiffening and also for the purpose of anchoring the panels. The lips 103C extend toward each other.

35 In FIG. 28, wall panels 29, with recesses 29A and through openings 29B are illustrated, and are anchored in a manner similar to the manner used to anchor the previously described panels 5 and 29. The anchoring may be effected by sufficiently rigid metal wires 105 40 extending through the openings 29B and having inner ends 105A bent over lips 103C. These wires, each of which extends through the holes 29B of two adjacent panels, are tied to one another as indicated at 105E, with the tie lying in the recess or depression 29A which 45 is later filled with stucco covering the tie. Adjacent panels 29 are additionally tied to one another by metal wires 107, also extending through the holes 29B, and tied to each other as indicated at 107E. The panels may 50 also have their edges cemented or glued to each other.

55 On the left side of FIG. 28, as viewed in the drawing, and in FIG. 29, there are illustrated panels 110 which may be formed in a manner different from the manner used to form the sand-cement panels previously described. Thus, the panels 110 may have an outer surface finishing. Panels 110 may be manufactured by pressing in the same manner as used for forming cement tiles, to provide a first outer layer 110A of precious and selected materials and a second inner layer 110B formed by a mixture of sand and cement. The outer layer 110A may have a uniform appearance or 60 may have several colors arranged in such a manner as to form a pattern or, alternatively, to provide a predetermined esthetic aspect. The outer surface of a panel 110 may be finished during the pressing or subsequently by using a smoothing operation.

65 A surface-finished panel, such as a panel 110, must be anchored in a manner such as to avoid possible visi-

bility of the means anchoring the panel to the wall skeleton. For this purpose, they may be fixed by means of threaded connections accommodated in thin through holes utilizing a limited stucco covering, or they may be anchored by a rear anchoring system in which case, in a wall having two panels, only one panel may comprise a finished panel such as the panel 110. In the arrangement shown in FIGS. 28 and 29, panels 110 have recesses 110C on only their inner surfaces, and these recesses are formed with blind holes, formed by pressing, receiving metal elements 112 of the nature of a pin or the like and anchored therein. These pins 112 are formed with chordal slots 112A facing outwardly with respect to the recesses 110C. The pins 112, 112A serve for interconnecting adjacent panels 110 by means of metal wires 114 which are tied together to form links received in the recesses 110C. Pins 112, 112A serve also to anchor the panels 110 to the transverse components 103, with the aid of metal elements 116 each of which is formed with two slits extending in respective opposite directions. One slit or slot is used to anchor the element 116 to the lips 103C of the transverse components, and the other slit or slot receives a metal wire 118 also engaged in a slot 112A and forming a loop connecting the associated pin 112 to the associated element 116. Panels 110 may also be cemented or glued together along their abutting edges.

A wall surface formed with panels 110 and anchored on its rear surface to the wall skeleton may require no finishing, while a wall surface formed with panels 29, or the like, and which involve filling of the depressions and holes with stucco, may be finished with paint, with the application of wallpaper, or the like.

Whichever setup of the metal skeleton and the paneling is used, sound-proofing and lagging insulating thicknesses, especially those of an elastic material, may be interposed between the paneling and the skeleton. As shown in FIG. 28, washers 120, of elastic material, are interposed between the panels and the flanges 130B of the transverse components. Suitable recesses to accommodate at least partially the thickness of washers 120 or other insulating pads may be formed in the panels, advantageously during pressing of the panels or during whatever other panel manufacturing process is used. The pads may be inserted into these recesses at least temporarily in order to facilitate assembly.

In the embodiment shown in FIG. 30 and the subsequent figures, a wall skeleton is formed of lattice work or cage type metal elements, which are substantially equivalent to each other in this structure, and which form the posts and transverse components. In particular, each transverse component comprises four square angles 201 defining a component which has substantially a square cross section. The four angles 201 are interconnected by the intermediate weirs or webs 203 and by end plates 205. As shown in FIG. 36, small tabs 205A are bent from peripheral recesses of these plates for centering in the interior of facing edges of profiles 207 forming portions of posts included in the wall skeleton. By means of bolts 209 having hook extensions, the metal elements, such as the lattice work components 201 and 205, are secured to the posts of the wall skeleton.

The posts of the wall skeleton include, in addition to the square profiles 207, end plates 211 and inclined intermediate plates or webs 213. Plates 211 also have small tabs 211A bent from recesses 211B thereof, the

recesses 211B being deeper than the length of the small tabs 211A extending from the edges of these recesses. Plates 211 serve for connection of the ends of wall guide posts, provided in the structure of a floor and under and against the structure of a floor or ceiling. For connecting these wall guides, which are described hereinafter, and which are arranged perpendicularly to each other, there may be provided plates 215 as shown in FIG. 36, these plates having shapes or contours for connection to the guides in a manner similar to the plates 211 of the posts 207. Consequently, plates 215 also have small tabs 215A extending from the side edges of deeper recesses 215B, the recesses being deeper than the widths of the tabs.

The lower wall guides are formed by shaped sections including two laterally spaced inverted U profiles defining a relatively wide central U-shape longitudinal recess, these guides having outwardly projecting flanges 217A on their lower edges. Two flat strips or profiles 219 are fixed on each lower guide 217, for example by welding, and these profiles project inwardly relative to the central recess to form two laterally spaced edges corresponding to the tabs 211A.

In a manner similar to the lower guides, there are provided upper guides 221 shaped and arranged symmetrically with respect to the lower guides, and with respect to a horizontal plane, but without any flanges such as the flanges 217A. Each upper guide 221 is also provided with two flat strips or profiles 223, and the inner edges of these profiles 223 are spaced apart a distance equal to substantially the width of tabs 211A and 215A. End plates 211 of posts 207, and the T-shaped intersection plates 215 of the guides, as shown in FIG. 36, are secured to the flat profiles of strips 219 and 223 by means of bolts 225 having T-heads seated in the respective recesses 211B or 215B and engaged with the respective tabs 211A, 215A.

FIG. 37 illustrates an angle 227 used to connect a post, such as a post 207, to a guide, such as a guide 217 or 221 which is perpendicular to that to which the post is secured with the assistance of tabs 211A and bolts 225. One leg of angle 227 has a recess with a tab 227A similar to the tabs 215A for cooperation with bolts 225, and the other leg has tabs 227B similar to the tabs 205A for connection to profiles 207, of a post, by means of hooked bolts 209.

FIGS. 38 and 39 indicate the junction between two contiguous portions of a wall guide, such as a lower guide comprising sections 217 and 217A with the associated flat strips or profiles 219. A slotted sleeve 229 is accommodated in the longitudinally extending central recess of the wall guide, in such a manner that flanges, extending inwardly from the edges of its slot, are juxtaposed with the inwardly extending portions of the profiles 219, or 223. By means of bolts 225, having a T-shaped head, sleeve 229 is fixed to the two contiguous and aligned sections of the wall guide to establish a rigid connection therebetween.

The wall skeletons are formed by the lattice work or cage elements 201, 205 and 207, 211, and the panels are mounted on the wall skeletons. The skeletons are finished by adjustable portions, to be described, for adaptation to dimensions different from the modular dimensions of the lattice work or cage elements.

FIG. 33 particularly indicates two possible arrangements for connecting the panels to the profiles 201 of the horizontal wall skeleton elements. The panels are

formed of a material similar to that used in conventional masonry, and particularly of a sand-cement of the like, with or without surface finish, and with edges finished in an accurate manner for accurate matching and bonding of the abutting edges of adjacent panels. Panels 231 which are to be secured to the interior surface of the wall skeletons, and do not require any stucco covering, include pins 233 bonded thereto and extending rearwardly therefrom, these pins 233 being formed with slots by means of which the pins of adjacent panels may be interconnected by a binder 235 in correspondence with a wall skeleton element 201, 205. In addition, pins 233 may be connected to the wall skeleton elements with a binder 237 engaged in their slots and connecting the pins to buttons 239 having slots receiving the flanges of profiles 201, these flanges extending away from the panels.

Panels 241, capable of being fixed from the outside and requiring a subsequent stucco treatment, have recesses 241A with two holes 241B through which extend bolts 243 which have bent ends engageable with the edges of angular profiles 201 extending away from panels 241. Bolts 243 have outer threaded ends receiving nuts 245 which are advantageously formed with peripheral grooves to receive the binding connecting vertically abutting panels, the binding being indicated at 247. Recesses 241A in which nuts 245 and binder 247 are accommodated are later filled with a stucco covering 249 concealing the nuts and the binder. Each panel 241 advantageously has at least 4 recesses 241A, two on each longer side. The panels of the lower row of a wall rest on the flanges 217A of a lower wall guide 217. Thicknesses of sound-proofing material and of thermic insulation are interposed between the panels and the metal elements of the walled skeleton or the wall guides.

Wall guides 217 and 221 are connected in a suitable way to the surfaces of the floor and sealing structures S and S1, respectively. Anchoring screws 251, as shown in FIG. 35, connected by nuts, lock nuts and stirrups to the flat strips or profiles 219 and 223 are advantageously provided to secure the wall guides in position and thus to secure the walls positioned properly with respect to the main supporting frame and thus to the structures S and S1. The ends of these anchoring screws project into appropriate line holes formed in the structures S and S1.

FIG. 40 shows another way in which two abutting panels 241 can be connected utilizing the recesses 241A and the holes 241B. As illustrated, a binder 253 extends through the holes 241B of the two adjacent panels, and is tied in the recess 241A. The recess may then be filled with a stucco covering 255.

FIG. 40 further shows the manner of connecting a post 207 to a wall stretcher extending perpendicular thereto. For this purpose, there are used joining clamps 257, 259, clamped together by means of bolts 261 to lock, at a suitable level, the angle profiles 207 to the angle profiles 201 which are in contact with each other and across each other. FIG. 40 also shows a particular type of bolt 263, useful in certain instances, such as for connecting portions of panel 265 to a metal skeleton and for other uses. Additionally, a binder 267 can be provided to connect a panel, or a portion thereof, to a profile 207 of a post.

FIGS. 41, 42 and 43 illustrate the manner of making a thick wall, such as an exterior wall, the arrangement

being similar, however, to constructing a thin intermediate wall. In particular, FIGS. 41 and 42 illustrate how a wall skeleton, which is either single or double, is connected to the main supporting frame whose elements define an opening to be closed by a wall. Two columns, laterally limitating the opening to be closed by the wall and forming part of the main framing, are illustrated at 269, with the opening being arranged to receive a wall skeleton formed by the metal lattice elements or cages 201, 205 and 207, 211. A substantial portion of the wall skeleton is formed by posts 207 with transverse components 201. The wall skeleton is completed by an adjustable portion to span the space between the two columns 269.

For this purpose, tubular cross members 271, in the nature of connecting sleeves, are provided between a post 207, generally indicated at 273 in FIG. 42, and another post 207, generally indicated at 275. These two posts, whose spacing must be adjusted using the tubular cross members or sleeves 271, are provided with plates 277 substantially similar to the plates 205 but independent of a lattice work or cage element. The plates 207 are formed with central apertures receiving a tubular cross member 271. The cross member 271 may be retained affixed with respect to one plate 277 by plugs 279 extending through the sleeve 271, and may be slidably engaged through the opening of the other plate 277. Connection means, comprising plates 281 and angular profiles 283 similar to profiles 201, and similarly arranged, are slidably mounted on each tubular element 271 to provide for anchoring bolts, such as the bolts 243, for securing the panels or parts of panels. With the wall skeleton formed in this manner, and adjustable as to its width, the aids of the sleeves 271, as well as being engaged with the wall guides, it is possible to assemble a single or double wall between two columns 269. For this purpose, the end posts are provided with plates 285 similar to plates 277 but having horizontal pins 287 extending outwardly relative to the wall skeleton. Each vertical end wall of a wall skeleton has several pins 287 and these are engaged in apertures or holes provided in the main framing in a slidable manner to allow settling and expansion.

As illustrated in FIGS. 41 and 42, a wall skeleton has its ends 287 engaged in plate stirrups 289 fixed to columns 269 by screws 291 or other suitable means. FIGS. 41 and 43, also, show how pins 287 may be engaged with the flange of a H-column 269. For this latter purpose, there is provided a U-shaped section 293 having end flanges and affixed to column 269 by means of screws, such as, for example, the same screws 291 securing the stirrups 289. Pins 287 are engaged in apertures in the base of the U-shaped section 293, while the end flanges of this section are pressed against column 269 or in equivalent structure.

FIGS. 41 and 43 further show the manner of connecting panels, such as the panels 241, at an angle or otherwise in correspondence with column 269. Stirrups, similar to the stirrups 289, may be used for bolts, such as the bolts 263, and also a profile 293A, similar to profile 293, may be used and connected in place by screws 291. Profile 293A, however, is connected to column 269 at its central portion, while its flanges are engaged by bolts 263 or the like, to secure the panels in position. Insulating spacers or shims also may be provided in the assembly of the panels to a column 269.

FIG. 42 also shows a connection between two adjacent laterally spaced wall skeletons to form a double or thicker wall. For this purpose, spacer members 295, welded to plates 297, and engaged with counterplates 299 to embrace the flanges of profiles 207, are used.

FIGS. 32 and 44 illustrate a beam 301 of a floor structure, in particular a peripheral floor beam, which is connected to columns 269 by the use of suitable plates secured to the columns 269. Plates 303, welded to a floor beam for connection to other beams, such as secondary beams 305 which have a H-profile, are illustrated. Beams 305 have end plates 307 welded thereto and these can be coupled to plates 303, or to other equivalent plates, by bolts 309 or equivalent connection members. It should be noted that the engaging surfaces of plates 307 and 303 are mechanically machined for a perfect matching. A plate 303 may serve further for securing a stirrup 311 engaging outer wall guides 221 and 217X, similar to guides 217 but without flanges 217A. Wall guides 217X are located along the series of outer panels 313 forming a continuous outer wall.

In FIGS. 32 and 44, there is illustrated a panel 241X provided with an upper finishing frame or contour adjacent to the ceiling. The ceiling is formed by panels 315 connected in place by bolts 243 or the like. Panels 315 may be of a type similar to that of the panels 241 or 231.

Stress resistant floor panels, which are even thicker than the panels previously described, are illustrated at 317 and form, when laid in place, the floor structure. Panels 317 are laid onto beams 301 and 305, as well as on connecting beams 319 extending between adjacent beams 305, and fixed thereto by plates 320 welded to beams 319 and by plates 321 welded to beams 301 or 303, screws 322 or the equivalent being used to secure the beams to each other. Supporting bolts for ceiling panels 315 and anchoring bolts of panels 317 may be anchored to the smaller beams 319. The floor lining or covering 321, combined with the base molding 323, is arranged on panels 317. Plates 321 may be used also for anchoring stirrups 311.

As seen in FIG. 32, columns 269 have end plates 327, welded and machined for accurate matching with corresponding end plates 329 of an upper column, the plates 327 and 329 being interconnected by clamping bolts. Furthermore, the main floor beams 301 and 305 are provided with end plates 303, 307, welded and machined for matching with counter-plates provided on the columns and on the beams. Plates, such as the plates 329 and other plates, may also form a step, for example for the resting and accurate positioning in height of the end plates 307 of the floor beams such as 305.

FIG. 32 also illustrates panels 331 of an outer wall, in which are supported by transverse components 201 and by sections 293A or other equivalent means. The outer wall is provided with a protective lining, for example one formed by shaped slabs of a porcelain sheet, as indicated at 333, these slabs being partially overlapped to form a continuous protecting surface. Slabs 333 may be supported, for example, with the aid of pins 335, secured to panels 313, and provided with grooves in which the edges of recesses, formed like wedges and provided in the inner supports of slabs 333 are engaged.

FIG. 31 illustrates how an impermeable covering or roofing may be provided. Trusses, generally indicated at 341, are used for this purpose, and they may be constructed like a framework and have an appropriate slope. The end stirrups 343 of the trusses serve for connection to floor beams, such as the beams 301. Panels 345 are laid onto trusses 341, 343 to form the surface on which the covering shell 347, having several impermeable layers, may be placed. This shell is extended, as indicated at 347A, to form a covering engaging end panels 349. The outer walls are completed, relative to the covering, with short posts 207, 211 and associated transverse components formed by the cage elements 201, 205. At the upper edge, wall guides 221X, similar to the guides 221, may be provided. A covering 351 covers the outer or intermediate walls so as to protect against penetration of moisture. This covering has lips or flanges extending over extension 347A and over the outer covering formed by the porcelain slabs 333.

The described prefabricated structures provide for a combination of conduits for different facilities or services in the gaps formed by the structures, both in the vertical direction and in the horizontal direction. The double walls, formed by two laterally spaced skeletons, may accommodate, between the two skeletons, suitable ties, such as turnbuckles 353 shown in FIGS. 45 and 46. The turn buckles can be anchored, by means of supports 355, to beams 301 and, by means of supports 357, to columns 269, these supports being welded, for example, on stirrups similar to the stirrups 289.

While specific embodiments of the invention have been shown and described in detail to illustrate the application of the principles of the invention, it will be understood that the invention may be embodied otherwise without departing from such principles.

What is claimed is:

1. A prefabricated building structure comprising, in combination, a supporting framework including columns and floor beams interconnected to each other and defining openings to be closed; upright components, having substantially flat side surfaces, and modular length transverse components, having substantially flat end surfaces; connecting means securing the flat end surfaces of said transverse components to the flat side surfaces of said upright components to form wall skeletons having flat limiting surfaces; means connecting said wall skeletons to said framework and to each other to define substantially rectangular openings; at least two sets of prefabricated molded modular length panels, of cementitious material, mounted on said wall sections and closing at least some of the openings therein; at least said transverse components having longitudinal flanges thereon; and mechanical means engaged with said flanges and securing said panels to at least said transverse components.

2. A prefabricated building structure, as claimed in claim 1, including lower transverse components provided with projecting plates engaged by the lower edges of said panels to support said panels.

3. A prefabricated building structure, as claimed in claim 1, including pairs of spacers adapted to interconnect upright components of adjacent wall skeletons to each other at adjustable distances to compensate for the difference between the overall length of a series of modular skeletons and the length of the opening to be occupied by the series.

4. A prefabricated building structure, as claimed in claim 1, in which the connection between a wall skeleton and said supporting frame is provided by pins slidably engaged in apertures to provide for relative movement between the wall skeleton and the supporting frame.

5. A prefabricated building structure, as claimed in claim 4, wherein said pins are secured to the upright components of a wall skeleton and the apertures are formed in columns of said framework.

6. A prefabricated building structure, as claimed in claim 1, in which said panels are pressed and molded panels with a precision shape and size, and formed with recessed seats for said mechanical means.

7. A prefabricated building structure, as claimed in claim 6, in which said panels have an exposed surface finished in the manner of ceramic tiles.

8. A prefabricated building structure, as claimed in claim 7, in which said panels have recesses formed on their rear surfaces adjacent their peripheries; pins projecting from said recesses and formed with grooves for the reception of metal wires interconnecting adjacent panels and connecting the panels to the wall skeleton.

9. A prefabricated building structure, as claimed in claim 8, in which said transverse components have longitudinal flanges on their side edges formed with inwardly bent lips at their free edges; and elements formed with two notches opening in opposite directions, one notch being engageable with the lip of a transverse component and the other notch being engageable with a metal wire securing a panel to the wall skeleton.

10. A prefabricated building structure, as claimed in claim 6, in which said panels have, in correspondence on opposite surfaces thereof and along the peripheries of the panels, seating recesses receiving said mechanical means; said recesses opening outwardly and said mechanical means extending from said recesses into engagement with flanges of said transverse components; said recesses having depths such that, when filled with stucco or the like, said mechanical means are completely covered.

11. A prefabricated building structure, as claimed in claim 1, in which said panels are formed, along their peripheral edges and on their safe surfaces facing the metal structure, recesses at least partially seating insulating layers interposed between said panels and the metal structure; said insulating layers serving to reduce the transmission of physical, particularly accoustic, phenomena.

12. A prefabricated building structure, as claimed in claim 1, including covering plate members covering the panels forming the exterior walls of said structure to form an impermeable covering; and engagement means secured in apertures of the panels forming the exterior walls; said covering plate members being fixed to said engagement members and closing an interspace.

13. A prefabricated building structure, as claimed in claim 1, including horizontal panels forming floors and ceilings of said structure; said horizontal panels being substantially identical with said first mentioned wall panels; said framework including supporting frames constructed of horizontal support beams; and means anchoring said horizontal panels to said support beams.

14. A prefabricated building structure, as claimed in claim 1, in which each upright component and each transverse component of said wall skeleton comprises

four elongated angles defining an open cage; end plates interconnecting the four angles; and intermediate plates interconnecting the four angles; the legs of said angles being arranged for engagement by said mechanical means for securing the panels to said wall skeletons.

15. A prefabricated building structure, as claimed in claim 14, in which components of said wall skeletons include connection squares; said end plates and said connection squares being formed with projecting tabs 10 serving for centering of the components by cooperation with spaced inwardly facing edges of a component perpendicular to the respective component; said structure including wall guides defining facing spaced inner edges also engageable with said tabs.

16. A prefabricated building structure, as claimed in claim 15, in which each tab extends from an edge of an associated recess; each recess receiving a threaded clamp having a T-head and which is retained between the bottom of the recess and the respective tabs.

17. A prefabricated building structure, as claimed in claim 16, including a pair of flat metal strips extending along the upper and lower sides of a wall skeleton and secured to profiled wall guides; said profiled wall guides being formed with inverted U-contours along each side and defining therebetween a U-shaped central longitudinally extending recess; the tabs of said end plates of the upright components being centered between said inverted U-contours.

18. A prefabricated building structure, as claimed in claim 17, in which end to end contiguous lengths of said flat metal strips and of said guides are interconnected by longitudinally slotted sleeves telescoped in said recesses; and bolts extending through apertures in said substantially flat plates and having T-shaped heads engaged in the slot of said sleeves.

19. A prefabricated building structure, as claimed in claim 18, including side plates formed with projecting centering tabs; threaded clamps securing said side plates to said components of said wall skeletons; said side plates having pins projecting therefrom and slidably engaged in apertures of stirrups secured to columns of said supporting metal framework.

20. A prefabricated building structure, as claimed in claim 19, including additional side plates formed with projecting centering tabs; threaded clamps securing said additional side plates to said components of said wall skeleton; said additional side plates being formed with apertures; tubular spacers accommodated in said apertures; and relatively short connection elements, having a construction corresponding to that of said components, slidably mounted on said tubular spacers and carrying mechanical means engaging panels extending into interspacers between upright components of wall skeletons, which wall skeletons are spaced an adjustable distance apart to compensate the overall length of a series of wall skeletons with respect to the modular lengths of the individual wall skeletons.

21. A prefabricated building structure, as claimed in claim 20, including spacer and connection members between wall skeleton components extending in space laterally spaced relation to form relatively thick outer walls; and plates and counterplates on said spacer and connection members clamping the legs of the angles of the laterally spaced wall skeleton components.

22. A prefabricated building structure, as claimed in claim 20, in which the columns and beams of the supporting framework are H-columns and beams; plates

secured to said columns and beams and having accurately machined surfaces; said plates providing for interconnection of the main and secondary components of said supporting framework in exactly perpendicular

relation to each other; said supporting framework including bracing and stiffening tie rods extending between horizontal and vertical components thereof.
